W. B. BRAUCHER

VENTILATOR

Filed Nov. 7, 1921

UNITED STATES PATENT OFFICE.

WILLIAM B. BRAUCHER, OF CHICAGO, ILLINOIS.

VENTILATOR.

Application filed November 7, 1921. Serial No. 513,351.

To all whom it may concern:

Be it known that I, WILLIAM B. BRAUCHER, a citizen of the United States, residing at Chicago, in the county of Cook 5 and State of Illinois, have invented certain new and useful Improvements in Ventilators, of which the following is a specification.

This invention relates particularly to ventilators of the injector and ejector type, and is especially adapted and intended for use in connection with motor vehicles, for the purpose of ventilating closed vehicles of that type having sliding windows. The device is however capable of use on railway 15 cars, houses and various other places.

Closed motor vehicles commonly have a glass window pane which can be raised or lowered, and the present device consists of 20 a ventilator which may be fitted upon the upper edge of the pane, in the window casting, where it will serve to ventilate the car while excluding rain or snow.

The invention is illustrated in the accompanying drawings in which Fig. 1 is a top plan or upper edge view of the ventilator. Fig. 2 is a side elevation thereof. Fig. 3 is an end elevation. Fig. 4 is a perspective of one of the hoods.

Referring specifically to the drawing, 30 6 indicates a board the thickness of which is preferably the same as the thickness of the window pane indicated at 7, to which the board is applied edgewise by means of a pair 35 of strips 8 secured to the lower edge of the board and forming a channel to receive the edge of the pane, whereby the board can be inserted in the window frame by lowering the pane sufficiently, the length of the board 40 being preferably equal to the length of the upper edge of the pane.

This board 6 is provided with two holes 9 spaced a short distance apart, and associated with each hole is a pair of hoods 10, 45 one hood of each pair being placed on the outside and one on the inside of the board. The hoods are tapered somewhat, as clearly shown in the drawings, and are provided with flanges 11 to receive fastening devices 50 to secure the same to the board; and the hoods cover or enclose the holes referred to. The hoods of each pair are presented oppositely, or forwardly and backwardly respectively.

Each hole 9 is controlled by a swinging 55 shutter consisting of a metal plate 12 located on the inside of the board and pivoted at 13 near the upper corner of the hood, the shutter being tapered to swing into and out of the hood and being held by its frictional contact with the surface of the board. When the shutter is swung in it closes the opening 9 and stops the action of the ventilator. When opened, it permits the inlet 60 and outlet of air through the respective 65 pairs of hoods.

When the car is traveling the air will enter the forwardly presented hood of one pair and will flow thence through the opening 9, and with a reverse direction through 70 the inner hood into the interior of the car. Air will also flow outwardly through the rearwardly presented pair of hoods, draft being induced by the air pressure in the car and the ejector effect of the outer air flowing 75 along the side of the car. Obviously by a manipulation of the shutters more or less air can be admitted or exhausted as desired. When not in use, the board can be removed from the window and stored within the car, in any convenient place. The device therefore provides simple and effective means for window ventilation without exposing the occupants of the car to a direct draft.

I claim:

1. A ventilator comprising a board adapted to removably fit a window frame, said board having a pair of openings through the same, and a pair of hoods enclosing each opening, the hoods of each pair being located on the inner and outer sides of the board respectively, the mouths of the hoods of each pair being presented in the same direction and in the opposite direction to the mouths of the hoods of the other pair.

2. A ventilator as set forth in claim 1, and shutters pivoted to the board and swinging in contact therewith into and out of the inner hoods of said pairs respectively, and across said openings respectively.

In testimony whereof, I affix my signature in presence of two witnesses.

WILLIAM B. BRAUCHER.

Witnesses:

WALTER F. COOLING,
W. H. COUGHENOUR.
